LOUIS STANGE, OF SOMMERDA, GERMANY, ASSIGNOR TO RHEINISCHE METALLWAAREN-
UND MACHINENFABRIK, OF DUSSELDORF-DERENDFORF, GERMANY, A CORPORATION
OF GERMANY

AUTOMATIC FIREARM

Application filed October 10, 1931, Serial No. 568,181, and in Germany October 20, 1930.

This invention relates to an automatic firearm wherein the closure member which has run back upon firing is again thrown forward by the hammer spring by means of the hammer. In the known weapons of this nature the spring which forms the hammer spring and closure spring exerts a driving effect upon the closure member only during a portion of the forward-running movement of the same, and indeed only until the hammer is held in its cocked position by the trigger. From that point on, the closure member, in order to give the hammer room for its subsequent igniting movement, continues its way alone, forwardly into the firing position, with the barrel, as a result of the momentum previously imparted thereto or, already connected with the previously retained barrel in a rearward tensioned position, is further carried along by its advancing means.

In the arrangement in accordance with the invention, the closure element during its whole forward movement in the firearm is subjected to the forward driving action of the hammer spring and the remaining-behind of the hammer necessary for the igniting movement is attained, or in other words the forward movement of the latter with respect to the hammer is produced, by elements arranged between these two parts, which during the closing movements are forced apart wedgewise, by positive guiding, between supporting surfaces of the closure element and the hammer.

These tensioning elements may be so formed and arranged that they themselves hold the forward running closure element and the hammer pressed apart in their mutual strained position until the firing and then either automatically, in dependence upon the running-in of the closure element into its forward end position, in the firearm, or, as by means of elements connected with the drawing device, are disengaged only by means of the trigger device, for freeing the hammer. It would also, however, be possible, aside from the tension elements proper, to provide special locking elements which will assume the function of holding the closure element and the hammer in the tensed posi-

tion given these two elements by the tension elements. The tension elements are movably located either on the closure element or on the hammer. Then the tensing takes place by turning the tension element carrier about the longitudinal axis relatively to the other part by means of a suitable cam guide in the closure housing.

The device in accordance with the invention is suitable for all automatic firearms having a longitudinally movable closure element, regardless of the arrangement of the barrel (stationary or sliding barrel), the nature of closure (latched or unlatched closure) and the firing device (direct "forward running firing" through the forward-snapping closure element, or indirect firing by a latching element of the trigger device, which still maintains the hammer under tension with a locked closure). The closure element is thereby disengaged positively from the hammer, in dependence upon the position of the hammer, and is brought forward with certainty into its forward end position in the firearm. The spring, which drives forward the hammer as well as the closure element, may, with a sliding barrel, also carry along the same back from its backward position, so that the special barrel-return device, heretofore necessary for this purpose, is eliminated.

The drawings show an exemplary embodiment of the invention in the form of an automatic firearm with a sliding barrel, latchable closure, and forward run firing, in longitudinal section, in various positions of operation.

In said drawings:

Fig. 1 shows the untensioned firearm with forwardly moved parts and latched closure, immediately after firing a shot.

Fig. 2 shows the same after the shot, with the barrel moved back and the closure element thereby unlatched during said running back thereof.

Fig. 3 shows the succeeding forward movement of the closure element at the instant of tensioning the hammer, and

Fig. 4 shows it shortly before firing the succeeding shot.

In the cylindrical housing *a* of the firearm are shiftably arranged the barrel *b* and the

closure shell *c* connected therewith. Into the closure shell *c* enters the closure element *d* which is so guided as to be longitudinally shiftable but not rotatable and is provided with locking threads *d*₁, and which is latchable with the closure shell by means of a counter-threaded member *e*₁ screwed upon the rear end thereof, with the locking threads *d*₁ of the ring *e* which carries the closure elements. The ring *e* is turned in known manner by means of a lug *e*₂ engaging in cam guides *a*₁ of the housing upon the moving of the closure shell *c*, for the unlocking or the subsequent locking of the closure, in known manner.

In the closure element *d*, is shiftably supported the hammer *f*, upon the thickened rear end *f*₁ of which presses a preliminarily tensioned spring *g* whose other end bears against the rear end surface of the housing *a* of the firearm. The same spring *g* constitutes at one and the same time the hammer spring, closure spring, and the forward-moving spring for the barrel. In the head *f*₁ of the hammer, is swingably supported a double armed tension lever or trigger *h*, one arm *h*₁ of which, acted upon by the first turn of the spring *g*, cooperates with the rear end surface of the closure element *d* and the second arm *h*₂ of which cooperates with an elongated lug *a*₂ of the housing *a* of the firearm, which projects into its path, in a manner which will be explained in greater detail hereinafter.

In the description of the operation of the firearm, let us consider first the position of the parts shown in Fig. 1, according to which the barrel *b* together with the closure shell *c* and the closure element *d*, which is locked thereby through the ring *e*, assume their forward end positions in the housing *a*. After the firing of the cartridge, which is located in the barrel, these parts first travel together in common a certain distance, in their locked-together condition, until, after the rotation of the locking ring *e* produced by the cam guides *a*₁ of the housing and the stopping of the closure shell *c* together with the parts *e* and *b* located thereon by means of a stop on the housing, not shown, the closure element *d* makes the return travel alone together with the hammer *f* supported therein. Hereby, by a travel of the tension lever arm *h*₂ over the elongated lug *a*₂ of the housing, the second arm *h*₁ of the tension lever *h* upon which the spring *d* presses directly, is swung to the rear. After sliding back behind the lug or strip *a*₂, the tension lever arm *h*₂, again returns to the position shown in Fig. 1, in which it projects into the field of the strip *a*₂; the hammer *f* itself attains its forward end position within the closure element *d*, that is, the firing position.

When the closure element *d* again runs forward under the influence of the spring

g acting thereon through the hammer *f*, the arm *h*₂ of the tension lever *h* strikes against the rear edge of the strip *a*₂ and is thereby transiently retained, while the hammer *f* and thereby also the closure element *d* continue their travel forwardly. The second arm *h*₁ of the tension lever *h* is swung forwardly against the end surface *d*₂ of the closure element *d* which is somewhat inclined forwardly, and thereby acting like a knee lever, gives to the closure element *d* a forward motion with respect to the hammer *f*, and to an extent necessary for the subsequent firing movement of the hammer *f*. The tension lever *h* remains in this tension position, thus given thereto, during the further forward movement of the closure element which first produces a locking of the closure element *d* with the closure shell *c*, heretofore retained in known way in its rearward position, whereupon the closure element *d*, the closure shell *c* and the barrel proceed ahead in locked-together position, into their forward end positions in the housing *a* of the firearm. The hammer *f* is thereby tensioned. Directly before the forward sliding parts reach their end positions in the housing, the arm *h*₂ of the tensioning lever *h* slides past the forward edge of the elongated lug or strip *a*₂ and the hammer *f*, under the pressure of the spring *g* which presses the tension lever arm *h*₁ sidewise, springs into the closure element *d* which meanwhile has come to rest, in order to fire forwardly the cartridge which has been introduced into the cartridge holder.

By suitable construction of the tension lever *h* and the controlling lug *a*₂ of the housing, the tensioning of the hammer *f* could also be accomplished even during the return movement of the closure element. The above described manner, of allowing the tensioning to take place only upon the running forward of the closure, is however more advantageous. Then the available path for the return of the closure element is not shortened by the backward movement of the hammer, and also no part of the momentum is withdrawn from the closure element, which, namely upon shooting with a great elevation, just suffices to return the closure element in opposition to the force of the forwardly moving spring to eject the fired-off shell and to feed in a new cartridge, to a sufficient distance backwards.

In place of the previously described "forward run" firing, wherein the tension hammer is released directly by the moving of the closure element into its forward end position in the housing of the firearm, an indirect firing could also occur by means of a locking element which still holds the hammer under tension when the closure of the cocking device is closed. For this purpose, as shown in Fig. 4 in dot and dash lines, it would be possible to insert in front of the housing strip or lug *a*₂ which swings the tension lever *h* into its

tensed position, a locking element *a*, disengagable by means of the trigger.

I claim as my invention:

1. Automatic firearm comprising a hammer, a closure element, a trigger element and a single spring which drives the closure element into its closing position and simultaneously drives the hammer forward into firing position, the trigger being located between the hammer and the closure element, said hammer and closure element each having bearing surfaces between which the trigger exerts a wedge action to drive them apart a distance equal to the necessary travel of the hammer for firing.
2. Firearm in accordance with claim 1, wherein the trigger element serves at the same time as a locking device for the cartridge feed, and suitable guide means in the firearm whereby the same is held in the tensed position given thereto, holding the closure element and the hammer pressed apart, up to the point where the closure element moves into its forward end position in the firearm.
3. Firearm in accordance with claim 1, comprising guide means whereby the trigger is brought into a position in the housing for producing the tensing of the hammer, only upon the return movement of the hammer and the closure element.
4. Firearm in accordance with claim 1, wherein the trigger element is swingably supported in the hammer or the closure element and serves as a tensioning element, and wherein in a stationary portion of the weapon cooperates therewith to swing it as a wedge between the hammer and the closure element during the closing movements.
5. Firearm in accordance with claim 1, wherein the trigger element is swingably supported in the hammer or the closure element and serves as a tensioning element, and wherein in a stationary projection of the weapon housing cooperates therewith to swing it as a wedge between the hammer and the closure element during the closing movements, whereby it is resiliently and yieldably forced into the field of the said projection by the hammer and the spring.
6. In testimony whereof I affix my signature.
LOUIS STANGE.
